UNITED STATES PATENT OFFICE.

OSCAR A. ROLLINS, OF CAMPELLO, MASSACHUSETTS.

IMPROVEMENT IN LUBRICATORS.

Specification forming part of Letters Patent No. **222,739**, dated December 16, 1879; application filed October 31, 1879.

To all whom it may concern:

Be it known that I, OSCAR A. ROLLINS, of Campello, in the county of Plymouth and State of Massachusetts, have invented a new and Improved Lubricator, of which the following is a specification.

Figure 1 represents a vertical elevation of the device, partly in section. Fig. 2 is a plan of the same on line *x x*, Fig. 1.

Similar letters of reference indicate corresponding parts.

This invention relates to that class of oil-pumps that are designed for supplying oil for lubricating purposes to steam-engine cylinders.

In the drawings, A represents the pump-cylinder, having in its lower head, B, two holes, *a a'*, to which the pipes *b b'* (shown in dotted lines, Fig. 1) are to be connected. Both of these pipes are to be provided with cocks, and one pipe is to connect with an oil-barrel or other reservoir, and the other with the steam-cylinder of the engine.

C represents the upper head of the cylinder, on which is a central boss or shoulder, *f*, whose vertical bore *c* is provided with a screw-thread, which thus makes, in effect, a nut of the said boss *f*; and D is a gear-wheel, whose socket *d* fits loosely over the shoulder *f* of the cylinder-head C.

The screw piston-rod E is passed centrally down into the cylinder A, through the cylinder-head C and the gear-wheel D, and carries on its lower end the piston F, and on its top the hand-wheel G.

The wheel D has no screw-thread cut in its bore, but is held to the piston-rod E by the key H, that is set in the keyway *g* of the wheel D itself, and in the longitudinal slot *h*, that extends the entire length of the screw on the rod E, so that when the wheel D is turned it carries the said piston-rod E around, screws it up or down in the cylinder-head C, remaining itself, however, in the same level.

K is a standard secured on the cylinder-head C, and supporting two pillow-blocks, L, that afford bearings to the worm-shaft M, on which is the worm N. On the outer end of

this worm-shaft is fixed the ratchet-wheel O. To the upward-projecting arm P of the standard K is pivoted the slotted arm Q, adjustable in the slot of which is a pin, *k*, that serves as a pivot for the pawl R.

S is a connecting-rod, designed to connect the arm Q with the motive power, by which the mechanism of the pump is operated.

When the piston-rod E and piston F have been screwed down as far as possible, and it is desired to fill the cylinder A, the cock *m* of the oil-supply pipe *b* is opened, and the cock *m'* of the pipe *b'*, connecting with the engine-cylinder, is closed, when the key H is removed from the gear-wheel D, and the piston-rod E is turned by means of the hand-wheel G until the piston F has reached the top of the cylinder A, in doing which it draws up oil from the reservoir into the said cylinder A. Then the cock *m* is closed, and the cock *m'* of the pipe *b'*, connecting with the engine-cylinder, is opened. The key H is then restored to its primary position to hold the gear-wheel D and the piston-rod E together. The pawl R is then allowed to engage with the teeth of the ratchet-wheel O. Then, if power be applied through the connecting-rod S, a reciprocating motion is imparted to the pawl R, which motion is transmitted, through ratchet-wheel O, shaft M, and worm N, to the gear-wheel D, and thence to the piston-rod and piston E F, so that the latter, being forced down at every stroke of the engine to which the pump is connected, ejects at each stroke a quantity of oil from the cylinder A through the pipe *b'*.

The quantity of oil ejected at each stroke of the engine or downward movement of the piston F is regulated by adjusting the pawl-pin *k* in the slot of the arm Q, for the higher up the said pin *k* is fixed in the arm Q the greater will be the leverage and sweep of the pawl R, and, consequently, the greater will be the extent of the motion it will transmit to the piston F through the ratchet-wheel O, and the greater, therefore, will be the displacement of oil by the said piston F at each stroke; while, on the other hand, the lower

the pin *k* is set, the shorter will be the sweep of the pawl *R*, and the less the consequent motion of the piston *F*.

Having thus fully described my invention, I claim as new and desire to secure by Letters Patent—

The standard *K*, provided with arm *P*, in combination with the cylinder *A*, shaft and

worm *M* *N*, ratchet-wheel *O*, pawl *R*, pin *k*, arm *Q*, and connecting-rod *S*, substantially as and for the purpose described.

OSCAR ALGENON ROLLINS.
